UNITED STATES PATENT OFFICE.

VINTON E. SISSON OF CHICAGO, ILLINOIS.

CARLINE.

1,093,657.

Specification of Letters Patent. Patented Apr. 21, 1914.

Application filed July 15, 1912. Serial No. 709,516.

To all whom it may concern:

Be it known that I, VINTON E. SISSON, a citizen of the United States, residing at Chicago, in the county of Cook and State of Illinois, have invented certain new and useful Improvements in Carlines, of which the following is a specification.

My invention relates to the construction of railway cars and has for its object to provide an improved form of pressed steel carline for the roof structure of a railway car.

The improvement consists in so shaping the carline that it will have a maximum load bearing strength at the middle where the load on the roof is greatest, and at the same time a maximum width at the ends where spread is necessary to check the tendency of the car to weave; and further, in providing a channeled carline with lateral flanges, the channel of which is deepest and narrowest at the middle and becomes shallower and wider toward the ends, the flanges of which are correspondingly narrow at the middle and wider toward the ends so as to give a maximum load bearing strength with a minimum amount of metal and hence a minimum weight, and, furthermore, so that the carline may be made from a piece of metal of uniform width, thereby minimizing cost of material and in obviating the necessity of trimming.

The improvement further consists in providing novel devices and arrangements for securely attaching the ends of the carline to the side wall structures of the car, and in providing the carline with certain other novel and advantageous features to be hereinafter more particularly described and claimed.

The invention is illustrated, in a preferred embodiment, in the accompanying drawings, wherein—

Figure 1 is a side elevation of the carline of my invention, certain other parts of the car structure being shown in section. Fig. 2 is a plan view of the structures shown in Fig. 1. Fig. 3 is an end view of my carline, showing it applied to the side plate of a car. Figs. 4, 5, 6 and 7 are sectional views taken on lines 4—4, 5—5, 6—6 and 7—7, respectively, of Fig. 2, looking in the direction of

the arrows. Fig. 8 is a view, in perspective, of one end of the carline, and Fig. 9 is a detail view, in perspective, showing a modification.

55

Like characters of reference designate like parts in the several figures of the drawings.

Referring first to Figs. 1 to 8 of the drawings, 10 designates the side plates of the car or other equivalent portions of the side wall structures, 11 the ridge pole and 12 the purlins.

The carline of my invention is preferably made of a sheet of steel of uniform width which is pressed into the form of a channel 65 with horizontally projecting side flanges. 13 designates the channeled portion of the carline, and 14 the side flanges which are preferably formed with the upturned rims 15 to give additional stiffness to the structure. The depth or vertical dimension of the channel 13 is greatest at the middle and diminishes toward the ends of the carline. This gives the necessary slope to the roof. The carline, on the other hand, is narrowest 75 at the middle and gradually widens toward the end in the same proportion as its vertical dimension decreases. The purpose of this is twofold. It is not particularly necessary to make the carline wide at the middle, 80 but depth at this point is important as the middle of the carline must carry the greatest load. On the other hand, the ends of the carline do not need to be so deeply channeled since they carry a comparatively light 85 load, but it is very desirable to give them as wide a spread as possible in order to check the tendency of the car to distort on diagonal lines or, as it is called, to weave.

It will be seen that the gradually increased width of the carline from the middle to the ends, which is proportioned inversely to the depth of the channel, is equally distributed between the channel and the flanges. That is, as the channel widens 95 the flanges widen also. As a result the metal at each point lengthwise of the carline has a symmetrical distribution with respect to the transverse neutral axis passing through said point. Or, to put it another way, at any cross section the combined width of the flanges equals, substan-

tially, the width of the middle web of the channel. Since steel has substantially the same strength in compression as in tension, a steel carline so formed will possess a maximum amount of load bearing strength for a minimum amount of metal, hence of weight, which latter is an important consideration in car building. As a matter of fact the strongest argument against the use of steel carlines in wooden box cars is that they tend to make the car heavy, and not only heavy, but top heavy. It is of the utmost importance, therefore, in carline construction to minimize weight as far as is consistent with obtaining the necessary strength. The other purpose of giving the carline this particular configuration is to permit it to be made from a sheet of metal of uniform width without the necessity of trimming.

20 The decrease in depth of the channel from the middle to the ends is just proportioned to the increase in width of the carline so that the sheet of metal is not distorted in the pressing and no metal is wasted.

25 The top of the channel 13 has the extension 16 at each end of the carline, the end 17 of which is bent down as best shown in Fig. 8. The flanges 14 are formed with extensions 18 which are also bent downwardly at right angles to the carline. When put in place in the car the extensions 18 bear against the inner surface of the side plates while the angular extensions 16, 17, at each end of the carline, extend over the top of the side plates and overlap the same on the outside. Bolts 19 are employed for securing the carline to the side plates. In order to strengthen the carline against the tendency to shear off the extensions 16, 17, the top 40 of the channel is formed at the end with a corrugation 20 which extends over upon the extension 16. Preferably the metal is struck downwardly to form the corrugation, in which case the side plate is correspondingly 45 grooved.

The top of the channel is preferably formed with a pair of transverse ribs 21 between which the ridge pole 11 is seated, and with ribs 22 for positioning the purlins 12.

50 The purlins and ridge pole may be secured to the carline in any suitable way, for example, by means of the bolts 23.

In Fig. 9 I have indicated a possible modification whereby the position of the carline is reversed, with the channel, designated 13^a, opening upward. The side flanges 14^a are formed with angular extensions 18^a which extend over the top of the side plate 10^a. The bottom of the channel 60 is formed with the angular extension 17^a which bears against the inside of the side plate.

While I have described my invention in a preferred embodiment, it will be under-

stood that certain modifications might be made without departure from the invention. Therefore I do not wish to be understood as limiting the invention except as the particulars shown and described are made specifically limitations in certain of the 70 claims herein.

The term "top of the channel" used in certain of the claims has reference to the preferred arrangement of the carline shown in the first eight figures. With the carline 75 reversed as shown in Fig. 9 this part, of course, becomes the bottom of the channel and the claims containing this expression should be read with the understanding that if desired the carline might be reversed so 80 that the channeled portion extends downwardly instead of upwardly.

I claim:

1. A pressed steel channeled carline formed with lateral flanges, the channel of 85 which is deepest at the center of the carline and becomes shallower toward the ends, the width of the channel and the width of the flanges being least at the middle of the carline and increasing toward the ends. 90

2. A pressed steel channeled carline formed with lateral flanges, the channel of which is deepest at the center of the carline and becomes shallower toward the ends, the width of the channel and the width of 95 the flanges being least at the middle of the carline and increasing toward the ends, said flanges being formed with angularly disposed stiffening rims.

3. A carline consisting of a sheet of steel 100 of uniform width pressed so as to form a channel, and flanges extending laterally therefrom, with the depth of the channel diminishing and the width of the channel and of the flanges increasing from the middle of 105 the carline toward the ends in such proportion that at any cross section the combined width of the flanges equals, substantially, the width of the middle web of the channel.

4. A pressed steel carline in the form of 110 an inverted channel having laterally extending flanges, with the middle web of the channel extending at opposite ends beyond the side webs thereof so as to be attachable to the side plates of a car and with the 115 flanges likewise longer than said side webs with their extremities bent downwardly so as to bear against the inner surfaces of the side plates.

5. A pressed steel carline in the form of 120 an inverted channel having laterally extending flanges, with the middle web of the channel extending at opposite ends beyond the side webs thereof so as to be attachable to the side plates of a car and with the 125 flanges likewise longer than said side webs with their extremities bent downwardly so as to bear against the inner surfaces of the

side plates, the middle web of said channel being formed at each end with a pressed out rib which extends over the portion of the same which overlaps the side plate.

5 6. A pressed steel channeled carline formed with lateral flanges, the middle web of the channel and said flanges being longer

than the side webs and disposed so as to form attaching flanges for attaching said carline to the side plates of a car.
